HYDRAULIC BROACHING MACHINE

Kenneth C. Monroe, Hudson, Mass., assignor to
The Lapointe Machine Tool Company, Hudson,
Mass., a corporation of Maine

Application October 18, 1937, Serial No. 169,581

3 Claims. (Cl. 90—33)

This invention relates to a hydraulic broaching machine of the type which is operated by a reversible discharge pump, such as the pump shown in West Patent No. 1,722,832. When such a 5 broaching machine is made of large size and is designed for heavy work, the operating pump must be correspondingly large and heavy, and the manual reversal of the pump twice for each broaching operation causes fatigue of the operator if continued over an extended period of time.

It is the general object of my invention to provide a broaching machine having mechanism for reversing the pump by power but under the continued control of the operator.

15 A further object is to provide a broaching machine having control apparatus which becomes inoperative as soon as released by the operator and which normally leaves the machine free for manual control.

20 In the preferred form of my invention, the control apparatus is so designed and constructed that the machine may be stopped manually at any point in its working stroke and that it will be stopped automatically at each limit of broaching 25 movement.

25 A further object of my invention is to provide control apparatus for reversing a pump in a hydraulic broaching machine, which apparatus may be placed in any desired or convenient location 30 with respect to other parts of the machine and in reference to other duties of the operator.

35 My invention further relates to arrangements and combinations of parts which will be herein-after described and more particularly pointed out in the appended claims.

A preferred form of the invention is shown in the drawings, in which

Fig. 1 is a diagrammatic side elevation, partly 40 is section, showing parts of a hydraulic broaching machine embodying my invention;

Fig. 2 is a side elevation, partly in section, showing the control apparatus on an enlarged scale; and

45 Figs. 3 and 4 are detail sectional side elevations showing certain parts appearing in Fig. 2 but in different working positions.

Referring to the drawings, I have shown my 50 invention embodied in a broaching machine operated by a reversible discharge pump. The broaching machine is indicated as having a main hydraulic cylinder 10 in which a piston 11 is vertically slidable. The piston 11 is connected by a piston rod 12 to a ram or slide 14 having an offset portion 15 to which a broach B is detachably secured. The machine is indicated as being

of the pull-down type, in which the broach is drawn downward through the work during the broaching operation.

The main cylinder 10 is connected by pipes 20 and 21 to upper and lower ports in a reversible 5 discharge pump P, which ports serve alternately as intake or discharge. The details of the pump connections and its method of operation form no part of the present invention, which relates particularly to the power actuation of the pump reversing mechanism under manual control. The direction of discharge of the pump P is controlled by a sliding rack bar 25 engaging a gear 26 which in turn controls the position of a rocker plate 10 inside of the pump casing. For further information as to the details of the pump P, reference is made to the West patent previously cited.

15 The rack bar 25 is connected by a link 27, lever 28 and link 29 to a bell crank 30, and the horizontal arm of the bell crank is connected by a 20 link 31 to the lower end of a stop rod 32, provided with upper and lower adjustable stop collars 33 and 34.

A block 35 is mounted at the upper end of a 25 rod 36 carried by the extension 15 of the ram or slide 14. As the block 35 engages one of the collars 33 or 34, the rack bar 25 will be moved to place the pump P in neutral position, thus bringing the slide 14 to rest at its upper or lower limit of travel.

30 The bell crank 30 is also connected through a link 37 to a hand lever 40 by which the pump P may be manually controlled or reversed. When the hand lever 40 is moved downward, the broach B will be given a downward or working stroke and 35 when the hand lever is moved upward, the slide 14 will be returned to upward position.

In order that the mechanism of the pump P may be additionally moved by power under certain conditions, I connect the handle 40 by a 40 link 41 (Fig. 2) to the upper end of a piston rod 42 having a piston 43 mounted thereon and slidable in a cylinder 44.

The upper and lower ends of the cylinder 44 are connected by pipes 46 and 47 to spaced ports 45 in a valve casing 50 enclosing a valve chamber 51. A piston valve 52 is slidable in the valve chamber 51 and has spaced piston elements 53 and 54.

The piston 52 is mounted on a piston rod 56 50 extending through suitable glands in the ends of the valve casing 50. One end of the rod 56 has a pin and slot connection to a control lever 60. Springs 61 and 62 are mounted on the rod 56 which is provided with adjustable collars 63 against which the springs abut.

An air or hydraulic pressure pipe 70 is connected to the middle portion of the chamber 51, and exhaust pipes 71 connects both ends of the chamber 51 to the atmosphere.

- 5 5 When the handle 60 is free, the springs 61 and 62 cooperate to move the piston valve 52 to its middle or neutral position in which both pipes 46 and 47 are connected to the atmosphere as indicated in Fig. 4. This leaves the piston 43 free 10 10 from pressure, so that the hand lever 40 may be freely shifted, either manually or by the knock-off mechanism.

Assuming that the machine is stopped with the slide in raised position and with the pump P in 15 15 neutral, a working or down stroke may be started by shifting the lever 60 to the left as indicated in Fig. 2. This connects the pressure pipe 70 through the upper pipe 46 to the upper end of the cylinder 44, and connects the lower end 20 20 of the cylinder through the pipe 47 to the atmosphere. The lever 40 is then moved downward under power, shifting the pump P from neutral to working position. The working or down stroke of the broach then takes place.

- 25 25 As soon as the down stroke is started, the operator may release the control lever 60, whereupon the lever 60 and piston valve 52 connected thereto are immediately returned to the mid or neutral position shown in Fig. 4. At the end of 30 30 the down or working stroke the handle lever 40 and the pump reversing mechanism are returned to neutral position by the knock-off mechanism.

In order to thereafter return the ram or slide 14 to its up position, the control lever 60 is shifted 35 35 to the right to the position shown in Fig. 3, admitting pressure to the lower end of the cylinder 44 and connecting the upper end of the cylinder 44 to the atmosphere. The hand lever 40 is thus moved upward, shifting the pump reversing 40 40 mechanism to "up-stroke" position. The control lever may be released as soon as the up stroke has started and will be automatically returned to neutral position, all as previously described.

It will be noted that all pressures on the piston 45 45 52 are balanced at all times, so that there is no displacing force.

If the lever 60 is not released by the operator before the end of an up or down stroke of the slide 14, no harm is done, as the main cylinder 50 50 50 and piston 11 are many times larger and more powerful than the cylinder 44 and piston 43 and will readily displace the piston 43 against any pressure which is being exerted thereon.

Similarly, if the operator moves the lever 60 55 55 in the wrong direction from neutral position, no harm will be done. If the broaching machine has been brought to rest at the lower end of the stroke, the block 35 will be in engagement with

the collar 34 and will prevent downward shifting of the lever 40, even if the control mechanism is shifted to the position shown in Fig. 2. Similarly no upward movement of the lever 40 can take place when the slide has been stopped in upper position by engagement of the block 35 with the collar 33.

I have thus provided mechanism by which the discharge mechanism of a reversible pump may be moved by power under control of the operator but will at the same time be free for direct manual operation as soon as the control lever is released and at any point in the stroke. Furthermore, my improved control mechanism permits the usual knock-off devices of the broaching machine to operate in the usual manner and to bring the broaching slide to rest and the pump to neutral position at the end of each up or down stroke.

Having thus described my invention and the advantages thereof, I do not wish to be limited to the details herein disclosed, otherwise than as set forth in the claims, but what I claim is:

1. A hydraulic broaching machine operated by a reversible discharge pump and having a member connected to the discharge-reversing mechanism for moving said mechanism manually, pressure-operated means to move said mechanism by power, manually operated control means for said pressure-operated means, and automatic means to neutralize said pressure operated means as soon as said control means is manually released.

2. A hydraulic broaching machine operated by a reversible discharge pump and having a member connected to the discharge-reversing mechanism for moving said mechanism manually, pressure-operated means to move said mechanism by power, and manually operated control means for said pressure-operated means, said control means including a spring-actuated valve mechanism automatically returnable to initial mid position and thereby rendering said pressure-operated means inoperative when said valve mechanism is manually released.

3. A hydraulic broaching machine operated by a reversible discharge pump and having a member connected to the discharge-reversing mechanism for moving said mechanism manually, a cylinder and piston connected to move said reversing mechanism by power, a valve for said cylinder by which pressure can be admitted at either end of said cylinder while the other end is connected to atmosphere, said valve when in mid position connecting both ends of said cylinder to atmosphere, a manually-operated control device for said valve, and automatic means to move said valve to mid position when said control means is manually released.

KENNETH C. MONROE.
